UNITED STATES PATENT OFFICE.

WILLIAM L. PHILLIPS, OF NORMAL, ILLINOIS.

IMPROVEMENT IN FIRE-PLACE HEATERS.

Specification forming part of Letters Patent No. 146,472, dated January 13, 1874; application filed October 16, 1873.

To all whom it may concern:

Be it known that I, WILLIAM L. PHILLIPS, of Normal, in the county of McLean and in the State of Illinois, have invented certain new and useful Improvements in Heating Apparatus; and do hereby declare that the following is a full, clear, and exact description thereof, reference being had to the accompanying drawings and to the letters of reference marked thereon, making a part of this specification.

The nature of my invention consists in the construction and arrangement of an open-fire heating apparatus so arranged as to combine the direct radiation of the cheerful open fire and the conduction of heat by warmed air, the object being to retain the open fire or direct radiation and to warm the extreme parts of the room in which the heater is placed, and, if desired, adjoining rooms, and to supply the heating apparatus for this purpose with air taken either from the room or directly from out-doors.

In order to enable others skilled in the art to which my invention appertains to make and use the same, I will now proceed to describe its construction and operation, referring to the annexed drawing, in which—

Figure 1 is a front elevation of the apparatus, broken so as to show the interior parts from the front. Fig. 2 is a transverse vertical section of the same, and Fig. 3 is a plan view with the top grating removed.

A represents the fire box or back cast in one solid piece and provided with one or more conduits, *a*, for smoke. These conduits form part of the fire-back, and are cast with the same, making all one continuous piece of iron. The fire-back A is made greater in width at the front than a true circle, so as to prevent cross-radiation, and let the rays radiate as much as possible into the apartment. B represents the drum or smoke-chamber, into which the conduit or conduits *a* deliver the products of combustion, and which may be made with or without an opening through the center to admit the passage of heated air that touches the heated iron below, and to increase the surface for air to come in contact with. C represents the double bottom or chamber in the base of

the heating apparatus. The bottom plate, *b*, of this chamber is represented as having two holes, *e e*, for the admission of air to the back of the grate or fire-box. The upper plate, *d*, of the chamber C, forming the ash-pit, is beveled or raised from *x* to *x* for the purpose of affording space for the admission of air. D represents the grate or fuel-basket, and E is the foot-rest in front of the same. G G' represent the casing to confine the air and compel it to pass upward. This casing is made in two sections, as shown, the lower section, G, being of cast-iron, and provided with an inner shoulder, *y*, at its top, to receive the upper section, G'. This latter section is made of russia-iron surmounted by a finished projection, *h*, which supports the open grating or register H.

By this construction of casing I am enabled to economize in both the cost and weight of the heating apparatus. The two sections are more easily handled in shipping, and can readily be attached or detached one from the other; and in case of the burning out of the drum or connecting-pipes, the sections can be easily taken apart and the injured parts replaced at little expense.

The smoke-drum B is made of common sheet-iron with cast-iron heads. The smoke enters the same at *a* and passes out through the pipe I to the flue or chimney.

A descending flue may be arranged on the back of the heating apparatus in such a manner as to allow of either a direct or indirect draft being used.

Having thus fully described my invention, what I claim as new, and desire to secure by Letters Patent, is—

The combination of the open fire-box A with pipe *a*, double bottom C, cast-iron casing G, shoulder *y*, sheet-iron casing G', drum B, and pipe I, all constructed substantially as and for the purposes herein set forth.

In testimony that I claim the foregoing, I have hereunto set my hand this 20th day of June, 1873.

WILLIAM L. PHILLIPS.
